UNITED STATES PATENT OFFICE.

GILBERT G. WHITE, OF MOORESVILLE, ALABAMA.

HORSE-DRENCHING BIT.

1,121,435.

Specification of Letters Patent. Patented Dec. 15, 1914.

Application filed April 20, 1914. Serial No. 833,257.

To all whom it may concern:

Be it known that I, GILBERT G. WHITE, a citizen of the United States, residing at Mooresville, in the county of Limestone and State of Alabama, have invented certain new and useful Improvements in Horse-Drenching Bits; and I do declare the following to be a full, clear, and exact description of the invention, such as will enable others skilled in the art to which it appertains to make and use the same.

This invention relates to new and useful improvements in drenching bits and the primary object of the invention is to provide a bit which may be quickly and readily applied to the head of an animal to enable medicines and the like to be forced down the throat of an animal.

A further object of the invention resides in providing a device which will enable a predetermined amount of the medicine to be administered.

Still another object of the invention, resides in providing a device which is simple and durable in construction, inexpensive to manufacture and one which will be very efficient and useful in operation.

With these and other objects in view, my invention consists in the novel features of construction, combination and arrangement of parts that will be hereinafter referred to and more particularly pointed out in the specification and claim.

In the accompanying drawings forming a part of this application:—Figure 1 is a perspective view of my device; Fig. 2 is a section therethrough; Fig. 3 is a similar view taken on a plane at right angles to that of Fig. 2.

In describing the invention I shall refer to the drawings in which similar reference characters designate corresponding parts throughout the several views and in which—

1 indicates a bit bar to the ends of which 45 are applied strips or cheek pieces 2 and 3, said cheek pieces being secured in any preferred manner. The cheek piece 3 depends on one side of the bit bar 1 to a greater extent than the cheek piece 2 and engaged 50 with the upper end of the cheek piece 2 is one end of a head stall or strap 4, the opposite end of said head stall or strap being adapted for engagement with the upper end of the cheek piece 3. This head strap or 55 stall may be adjustable if desired whereby to be applied on any sized head.

The bar 1 is tubular and extends completely through the cheek piece 3 and terminates in a tubular member or cylinder 6 which is designed to receive a liquid, such as medicine and the like. It might here also be stated that the cheek piece 2 has a cavity 2^a therein for receiving one end of the tubular bit bar 1. In receiving this end of the bit bar in the cavity 2^a, said cheek piece forms a closure for the last mentioned end of said bar and the bit bar and cheek piece 2 are secured one to the other at this connection by soldering, welding or any other similar means of securing the members. The opposite end of the bit bar 1, however, as stated above extends completely through the cheek piece 3, said cheek piece being provided with an opening 3^a for such purpose and in order to secure the cheek piece 3 in a rigid position with respect to the bit bar said cheek piece is soldered, welded, or otherwise similarly secured to the cylinder 6 which extends longitudinally thereof. This structure may be clearly seen in the showing illustrated in Fig. 2 of the drawing. This cylinder 6 which is indicated on the one side of the piece 3 has an inlet opening 7 therein and a discharge opening 5 is provided in the tubular bit bar 1. This discharge opening 5 in the bit bar 1 admits of the medicine or the liquid being discharged down the throat. Slidably mounted from the lower end of the cylinder or tube 6 is a piston or plunger 8 the shank 90 portion of which is provided with a scale indicated at 9 and the outer end of said shank is provided with a finger piece or knob 10 whereby to operate said plunger or piston in the cylinder 6. Applied on the shank of the piston 8 is a sleeve 11 in which is operatively mounted an adjusting screw 12 whereby to secure the sleeve in any adjusted position on the shank. In this manner predetermined amounts of the liquid in the cylinder or tube 6 may be forced into the tubular bit bar 1 to be in turn forced down the throat of the animal. Also secured to the lower end of the cheek piece or strip 2 is one end of a chin strap 13 said chin strap being adapted for engagement also with the cheek piece 3 whereby to secure the device in place on the head of the animal.

In operation, the device is applied to the head of the animal in the usual manner and the sleeve 11 is then adjusted on the shank of the piston 8 to permit said piston or

plunger to be forced inwardly in the cylinder 6 to the desired extent. The plunger 8 is then forced inwardly in said cylinder and the liquid in the latter will obviously be forced through the bit bar into the mouth of the animal. In this manner any predetermined amount of liquid may be administered, as desired.

From the foregoing description of the construction and operation of my improved device it will be seen that I have provided a drenching bit which is simple and durable in construction, inexpensive to manufacture and one which will be very efficient and useful in operation.

While I have particularly described the elements best adapted to perform the functions set forth, it is obvious that various changes in form, proportion and in the minor details of construction may be resorted to without departing from the spirit or sacrificing any of the principles of the invention.

Having thus particularly described my invention, what I claim is:—

In a drenching bit, a pair of cheek pieces, one of which is of greater length than the other and provided with an opening therein

adjacent its upper end, the other cheek piece being provided on its inner face with a cavity alining with the opening in the first mentioned cheek piece, a tubular bit bar having an outlet opening about central thereof and having its one end received and secured in the cavity of the last mentioned cheek piece, 35 said cheek piece having a rigid connection with the bit bar and forming a closure therefor, the opposite end of said bit bar extending through the opening in the first mentioned cheek piece, a tubular receptacle 40 formed integral with the extending end of said bit bar to form an angular continuation thereof, said tubular receptacle being disposed longitudinally of and secured to the outer face of the first mentioned cheek piece, 45 means whereby a liquid may be introduced to said receptacle and means for forcing a predetermined amount of liquid from the receptacle through the bit bar.

In testimony whereof I have hereunto set 50 my hand in presence of two subscribing witnesses.

GILBERT G. WHITE.
